SUNTAN VENDING MACHINE

Theodore Berkeley, Utica, N. Y.

Application September 6, 1955, Serial No. 37,785

Term of patent 14 years

(Cl. D52—3)

The figure is a perspective view of a suntan vending machine showing my new design.

The back thereof is plain or conventional. The undisclosed side of the vending machine is substantially the same in appearance as the side shown.

I claim:

The ornamental design for a suntan vending machine, as shown and described.
